UNITED STATES PATENT OFFICE.

LOUIS WOJIDKOW, OF BROOKLYN, NEW YORK, ASSIGNOR TO NEW YORK STAMPING COMPANY, OF BROOKLYN, NEW YORK, A CORPORATION OF NEW YORK.

ALCOHOL-LAMP.

1,070,650.

Specification of Letters Patent. Patented Aug. 19, 1913.

Application filed October 9, 1912. Serial No. 724,889.

To all whom it may concern:

Be it known that I, LOUIS WOJIDKOW, a citizen of the United States, residing at Brooklyn, in the county of Kings and State 5 of New York, have invented a certain new and useful Improvement in Alcohol-Lamps, of which the following is a full, clear, and exact description.

The object of this invention is to provide 10 a simple lamp, in which substantially all of the alcohol, or other burning fluid, is absorbed by the wick in the first instance, excepting that a slight overflow or excess may be utilized as a sort of primer or initial 15 burner, for heating the burner sufficiently to start vaporization of the fluid absorbed in the wick within the burner, and to ignite such vapor.

The invention comprises a holder having 20 a reservoir and a surrounding saucer-like flange, and a removable burner having a wick tube of substantially the same dimensions as the reservoir filled with any suitable wicking and adapted to be fitted in the reservoir, and in the act of being so fitted 25 therein to absorb substantially all of the burning fluid save a small quantity overflowed thereby into the saucer-like flange, which, when ignited will furnish heat 30 enough to start vaporization of the burning fluid within the burner and ignite it and thus establish the flame at the burner, which flame continues until the burning fluid is exhausted, unless sooner extinguished.

35 The invention is susceptible of a variety of embodiments, some of which are herein shown and explained in illustration of the principle of the invention.

In the accompanying drawings illustrating 40 the invention in the several figures of which like parts are similarly designated, Figure 1 is a top plan view; Fig. 2 is a side elevation; Fig. 3 is a top plan view of the holder, and Fig. 4 is a longitudinal section 45 illustrating one form of the lamp. Fig. 5 is an elevation of the burner detached. Fig. 6 is a longitudinal section showing the burner of Figs. 1 to 5 provided with a screen, as in Fig. 7. Fig. 7 is a half section 50 and elevation illustrating other modifications.

The holder comprises a tubular reservoir 1 having at its top a laterally extending saucer-like flange 2, preferably provided with an annular trough 3, and a handle 4. 55 Excepting that the reservoir is adapted to hold a given quantity of burning fluid and the flange is adapted to receive any overflow of such fluid, these parts may be of any approved construction and material. 60

The burner comprises a tube 5 adapted to be filled with any suitable wicking or absorbent material 6, and of a size to fit snugly within the reservoir and to absorb the fluid therein while being so fitted, in such way 65 that any surplus fluid will overflow into the flange and collect in the trough so as to furnish fluid to be ignited to serve as an initial burner in heating the burner proper sufficiently to vaporize the fluid within and 70 to ignite such vapor as it issues from the burner. A foraminous diaphragm 7 is secured within the upper end of the burner so as to limit the upward extension of the wick within such burner. Above this diaphragm 75 is the burner tip 8, of any suitable construction, and consisting preferably of a flared wall 9 provided with a perforated crown 10, the vapor collecting within the chamber 11 formed by the diaphragm 7, wall 9 and 80 crown 10 and issuing in jets through the perforations in the crown. The wall 9 overhangs the trough 3. The diaphragm may be held within a knurled or otherwise formed bead 12. 85

As shown in Figs. 4 and 5, the lower end of the burner may be left entirely open and scalloped or otherwise formed; or as shown in Figs. 6 and 7, it may be closed by a foraminous cap 13, frictionally or otherwise 90 engaging the burner tube. But it is preferred to make the burner in such way that the wick may be renewed whenever necessary, by any inexpert person.

Excepting for size and details of construction and shape, and the screwthreading presently described, the lamp shown in Fig. 7 is substantially like that already described. In order to prevent the operator from shoving the burner into the holder or 100 reservoir so suddenly as to preclude the absorption of the burning fluid by the wick,

and to splash out and waste such fluid, the upper portion of the holder or reservoir 1' is provided with a screwthread 14, and the upper portion of the burner tube 5' is provided with a complementary screwthread 15, so that the burner has to be turned into the holder in order to properly insert it therein. By this means the operator is prevented from thrusting the burner into the holder suddenly or violently. Moreover the screwthreads prevent accidental separation of the burner from the holder, and facilitate the disconnection of the two should they stick by the gumming of the fluid in burning.

In operation, the burner is removed from the holder, and a quantity of burning fluid is then placed in the reservoir, preferably enough to fill it. Then the burner, supplied with the necessary absorbent wick, is slowly placed in the holder so as to allow the wick to absorb the burning fluid. Some of the fluid will collect or overflow into the trough 3, and then when the burner is fully inserted within the holder a light is applied to the burning fluid in the trough, which is ignited, and by impinging on the wall 9 heats the burner sufficiently to vaporize the fluid, and the vapor issuing in jets through the crown is ignited by the flame from the burning fluid in the trough, and the lamp burns until its supply of burning fluid is exhausted or it is extinguished.

The lamp is useful for many purposes, but is especially useful where articles are to be cooked more or less, as eggs, for example, since by regulating the quantity of burning fluid, the lamp may be prepared to burn for any number of minutes. In this way, for example, eggs may be boiled soft, medium or hard without further attention from the cook.

These lamps may be made of any desired size, and of any desired fluid capacity, but I have found that a lamp two inches high, measured from the burner tip to the bottom of the holder, and with a flange of two inches diameter, will burn long enough to boil eggs hard. It is to be noticed that the burner fits the reservoir substantially tight, but not so tight as to prevent its easy removal. In inserting the burner in the reservoir, it may be dropped therein and allowed to settle by gravity, so as to avoid splashing, and in the case of lamps constructed in accordance with Figs. 1 to 6, the fit of the burner within the reservoir should be sufficiently tight to prevent the accidental displacement of the burner. In the form of lamp shown in Fig. 7, the screwthreading, as already stated, not only absolutely prevents the user from forcing the burner home in the reservoir suddenly, but admits of a loose fit between the burner and the reservoir, and also insures the retention of the burner in the reservoir against accidental displacement.

The lamp of Fig. 7 may be provided with any suitable handle, for example, one similar to that shown in Figs. 1 to 6.

Although the invention is entitled an alcohol lamp, and is so claimed, it is to be understood that the invention is not limited to the use of alcohol as the burning fluid. Any suitable vaporizable fluid may be used.

What I claim is:

1. An alcohol lamp, comprising a reservoir having a saucer-like flange surrounding its upper edge, and a removable burner, comprising a burner tube of substantially the same dimensions as the reservoir and provided with a wick and adapted to be fitted within the reservoir and its wick thereby absorbing substantially all the fluid within the reservoir, and a burner tip on said tube separated from the wick by a vapor chamber, the flange serving to receive fluid to be ignited beneath the burner tip to start vaporization in said burner.

2. An alcohol lamp, consisting of a holder which comprises a reservoir for the fluid, and a surrounding flange adapted to receive a quantity of burning fluid to be ignited for starting vaporization, and a removable burner comprising a wick-receiving tube of substantially the same dimensions as the reservoir and adapted to fit the reservoir, a foraminous diaphragm in the wick tube to limit the inward projection of the wick, and a tip made up of a side wall overhanging the flange, a perforated crown, and a vaporizing chamber interposed between the foraminous diaphragm and the crown.

3. An alcohol lamp, comprising a reservoir having a saucer-like flange surrounding its upper edge, said flange having a fluid receiving trough, and a removable burner tube of substantially the same dimensions as the reservoir and provided with a wick and adapted to be fitted within the reservoir and its wick thereby absorbing substantially all the fluid within the reservoir, and a burner tip on said tube separated from the wick by a vapor chamber, the trough serving to receive the fluid to be ignited beneath the burner tip to start vaporization.

4. An alcohol lamp, comprising a reservoir, having a saucer-like flange surrounding its upper edge, said flange having a fluid receiving trough, and a removable burner tube of substantially the same dimensions as the reservoir provided with a wick and adapted to be fitted within the reservoir and thereby absorbing substantially all the fluid within the reservoir, and a burner tip on said burner tube separated from the wick by a vapor chamber, the trough serving to receive the fluid to be ignited beneath the

burner tip to start vaporization, the wick-receiving tube having a foraminous cap in its bottom.

5. An alcohol lamp, comprising essentially a holder composed of a reservoir having a screwthread at its upper end, and a saucer-like flange extending laterally from said upper end, and a removable burner comprising a burner tip and a wick-receiving

13
ing tube of substantially the same dimensions as the reservoir and screwthreaded to engage the screwthread of the reservoir.

In testimony whereof I have hereunto set my hand this 7th day of October A. D. 1912.
